CLAIM

The ornamental design for a refillable hanger for moth crystals or the like, as shown and described.

DESCRIPTION

FIG. 1 is a perspective view of a refillable hanger for moth crystals or the like embodying my new design;

FIG. 2 is a front elevational view thereof;

FIG. 3 is a partial rear elevational view thereof; and,

FIG. 4 is a left end elevational view thereof, the right end being a mirror image.

FIG. 1

FIG. 2

FIG. 4

FIG. 3
